UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

RAILWAY SIDE FRAME.

1,351,326.

Specification of Letters Patent. Patented Aug. 31, 1920.

Application filed October 28, 1919. Serial No. 333,903

To all whom it may concern:

Be it known that I, CLAUS J. WERNER CLASEN, a citizen of the United States, residing in the city of Davenport, county of Scott, and State of Iowa, have invented certain new and useful Improvements in Railway Side Frames, of which the following is a specification.

My invention relates to side frames for car trucks and has as its principal object the provision of an improved side frame of the integral journal box type which shall possess the characteristics of increased strength and durability combined with economy of manufacture.

The novel features of my invention are pointed out with particularity in the appended claims. The invention itself, however, with further objects and advantages, will best be understood from the following description taken in connection with the accompanying drawing in which

Figure 1 is a top plan view of a side frame according to my invention;

Fig. 2 is an elevational view of the side frame illustrated in Fig. 1, part being broken away;

Fig. 3 is a transverse sectional view of the frame shown in Figs. 1 and 2, taken on the line 3—3 of Fig. 1;

Fig. 4 is a section on the line 4—4 of Fig. 2;

Fig. 5 is a section on the line 5—5 of Fig. 2;

Fig. 6 is a section on the line 6—6 of Fig. 2;

Fig. 7 is a section on the line 7—7 of Fig. 2;

Fig. 8 is a section on the line 8—8 of Fig. 2;

Fig. 9 is a section on the line 9—9 of Fig. 2;

Fig. 10 is a section on the line 10—10 of Fig. 2.

The side frame illustrated in Figs. 1 to 10 inclusive comprises longitudinally extending top and bottom members or chords 1 and 2 respectively, and two columns or struts, such as 4, extending between members 1 and 2.

The top member 1 is connected to the bottom member 2 at points near the ends of the frame. Struts 4 divide the space between members 1 and 2 into three apertures, the central one of which is roughly quadrilateral, and the other two of which are roughly triangular. The members 1 and 2 are channel shaped or U-shaped in cross section throughout most of their lengths, the central webs of these members being on top in the case of member 1 and at the bottom in the case of member 2. Struts 4 are integral with members 1 and 2 and are also channel-shaped or U-shaped in cross section, the central plates or web of these struts being on the sides toward the said central aperture.

I provide outwardly-extending beads, such as 5, around the edges of said triangular apertures, said beads being widened outwardly in sectors near the lower ends of struts 4 to form flanges such as 6. The outwardly-extending flanges 6 serve to reinforce the frame at the angles formed between struts 4 and chord 2.

Between the struts 4, the chord 2 has an upper central or horizontal web 8, and in this sector the chord 2 has also outstanding flanges, such as 9, at each side thereof in the same plane as web 8, forming therewith a spring seat 10 in which is an aperture 11 for interlocking the spring plank, not shown, with the side frame. It is evident that in the sector between the struts 4, except at aperture 11, chord 2 is of box section.

The top member 1 extends somewhat beyond the points of junction between itself and the bottom member 2, and in the angle thus formed I provide journal boxes, such as 12, which are integral with members 1 and 2, the central webs of chords 2 merging into the side walls of the boxes as illustrated in Fig. 4. The top member 1 extends across the tops of the journal boxes 12, the depending flanges of member 1 being integral with the tops of the boxes. Member 1 is preferably open at both ends as appears at 13 to permit the ready removal of cores.

The brake beam hanger brackets 14 are also preferably integral with the frame, extending rearwardly, at the upper angles of the said triangular apertures near the upper ends of struts 4.

While I have shown and described a side frame of specific outline, I do not wish to be limited to this.

It will be seen that a side frame according to my invention in which the chord and column members are of U section and the chord members integral with the journal

boxes is of great strength, especially when the upper chord member extends over the tops of the journal boxes, thus forming an integral box section therewith. It will be seen also that the projecting flanges 6 increase the strength of the entire frame without materially increasing its weight, while the box section at the spring seat also reinforces the entire structure.

10 Having thus described my invention, I claim:

1. An integral metallic side frame for car trucks, comprising column members, a top member, a lower member, and a journal box at each end of said lower member, said column, top and bottom members being all of **U** section, said top member extending above the tops of said journal boxes.

2. An integral metallic side frame for car trucks comprising column members, a top member, a lower member, and a journal box at each end of said lower member, said column, top and bottom members being all of **U** section, said top member extending above the tops of said journal boxes and forming a box-like structure therewith.

3. An integral metallic side frame for car trucks comprising column members, a top member, a lower member, and a journal box at each end of said lower member, said column, top and lower members being of **U** cross section, said lower member comprising a spring seat which closes the **U** between said columns, said top member extending above the tops of said journal boxes.

4. An integral metallic side frame for car trucks comprising columns, a top member, a lower member, and a journal box at each end of said lower member, said column, top and lower members being of **U** cross section, the said lower member comprising a spring seat designed to interlock the spring plank

with the side frame, said top member extending above the tops of said journal boxes.

5. An integral side frame for car trucks 45 comprising columns, a top member, a lower member, a journal box at each end of said lower member, and brake beam hanger brackets attached to the back of the frame, said column, top and bottom members being 50 all of **U** section, said top member extending above the tops of said journal boxes.

6. An integral metallic side frame for car trucks comprising columns, a top member, a lower member, and a journal box at each 55 end of said lower member, said column, top and bottom members all being of **U** section, said column members being spaced to form a bolster opening, the free edges of the **U** shaped members bounding, on each side of 60 the central bolster opening, an opening of substantially triangular shape, said top member extending above the tops of said journal boxes.

7. An integral metallic side frame for 65 car trucks comprising columns, a top member, a lower member, and a journal box at each end of said lower member, said column, top and lower members being of **U** section, said **U** shaped column and lower 70 members having flanges extending outwardly from their free edges at their points of juncture.

8. An integral metallic side frame for 75 car trucks comprising columns, a top member, a lower member and a journal box at each end of said lower member, said column, top and bottom members being of **U** section, said column members being spaced apart to form a central bolster opening and 80 having their central webs bounding said opening, said top member extending above the tops of said journal boxes.

CLAUS J. WERNER CLASEN.
